CONTROL MECHANISM FOR FLUID FUEL BURNERS

David J. Howard and Samson J. Johnson, Chicago, Ill., assignors to Quaker Manufacturing Company, Chicago, Ill., a corporation of Illinois

Application April 6, 1939, Serial No. 266,340

14 Claims. (Cl. 236—1)

This invention relates to certain new and useful improvements in control mechanism for fluid fuel burners, especially oil burners of the open pot type.

The invention provides improved mechanism for proportionately controlling, preferably in response to temperature changes in the space being heated by the burner, the flow of fuel and combustion air to the burner chamber. The fuel flows to the burner chamber through a pipe or passage provided with an adjustable valve mechanism adapted, even when the valve is given its maximum closing movement, to permit a minimum flow of fuel to the burner sufficient to maintain a pilot flame. This valve may be successively adjusted in the opening direction to provide the burner with fuel for a medium fire, or for a maximum or high fire. A suitable blower or fan forces air under pressure through a conduit to the burner chamber to provide the necessary combustion air for the medium or high fires. This air conduit is provided with an auxiliary opening in one of its walls through which air may be drawn in by natural draft to furnish combustion air for the pilot flame when the fuel flow is cut down to a minimum. This auxiliary opening in the air conduit is provided with a damper mechanism movable to open or close the natural-draft opening and, under certain conditions, to direct more or less of the air under pressure from the fan through a portion of the auxiliary opening so as to cut down the supply of pressure air to the burner. Preferably the blower will not be in operation when the oil supply is cut down to the minimum to provide the low or pilot-flame. Electrically actuated mechanism, preferably controlled from a room thermostat, functions to progressively open the fuel valve as the room temperature falls. Connections, preferably mechanical, are actuated by the valve adjusting mechanism to progressively adjust the damper mechanism so that the supply of combustion air to the burner will be properly proportioned to the fuel supply at all times. Preferably means is associated with the damper mechanism and operated by the pressure of air delivered from the blower to permit opening movement of the valve mechanism only when the blower is in operation, the fuel supply being automatically cut down to a minimum whenever the blower stops. This invention covers certain improvements on the control system disclosed and claimed in the copending application of Schreuder, Serial No. 219,269, filed July 14, 1938 **55**

which has matured into Patent 2,237,041 dated Apr. 1, 1941.

The principal object of this invention is to provide an improved control mechanism for fluid fuel burners as briefly described hereinabove and disclosed more in detail in the specifications which follow.

Another object is to provide improved means for proportionately adjusting the supply of fuel and combustion air to a hydrocarbon burner.

Another object is to provide improved means for controlling the air supply to a burner.

Another object is to provide improved means for selectively directing a portion or all of the flow of air from a continuously operating fan or blower to a burner.

Another object is to provide improved means for making the operation of a valve-opening mechanism dependent upon the flow of air from the blower.

Other objects and advantages of this invention will be more apparent from the following detailed description of one form of apparatus constructed and operating according to the principles of this invention.

In the accompanying drawings:

Fig. 1 is a side elevation of the complete burner assembly, the burner and a portion of the air-conduit being broken away in central vertical section.

Fig. 2 is a longitudinal vertical section through the damper-housing, this view being taken substantially on the line 2—2 of Fig. 3.

Fig. 3 is a horizontal section through the damper-housing taken substantially on the line 3—3 of Fig. 2.

Fig. 4 is a perspective view of the blower and control assembly shown at the left of Fig. 1.

Fig. 5 is a wiring diagram showing diagrammatically certain portions of the control mechanism.

Fig. 6 is a partial side elevation and partial central vertical section of the fuel-valve, the section being taken substantially on the line 6—6 of Fig. 5.

Fig. 7 is a wiring diagram similar to Fig. 5 but showing a modification.

The assembled apparatus as shown in Fig. 1 comprises the burner A adapted to be positioned within a furnace and connected by air conduit B with the fan or blower C and the assembly of controlling mechanism, indicated generally at D, positioned outside of the furnace. The mechanisms C and D are supported on a suitable base I carried by a plurality of adjustable sup-

porting standards 2. The burner end of the assembly is supported by a standard 3 having a ball-joint connection with the base 4. By properly adjusting the supports 2, the assembly can be pivoted about the rocking support 3 so as to properly level the burner A.

The burner A as here shown is of known type comprising an inner fire-pot 5 having an upright cylindrical side wall and a slightly concaved bottom 6 into which the fuel or oil is delivered from pipe 7 through inlet opening 8. The side walls of the pot 5 are provided with a plurality of air inlet openings 9 and 10 to support the combustion. The air supplied through conduit B flows into the exterior casing 11 around an intermediate shell 12 positioned between the inner and outer housings 5 and 11. The air flows from outer housing 11 through a large central opening 13 in the bottom of shell 12 and through a plurality of smaller openings 14 in the upper portion of shell 12 and thence through the pot openings 9 and 10 to support the combustion. The pot 5 is partially closed at the top by the annular baffle 15, and a pilot-ring or baffle 16 is positioned within the pot at an intermediate height, the ring 16 being supported on a plurality of inwardly projecting pins 17.

The fire is started by igniting the shallow pool of liquid fuel maintained on the bottom 6 of the pot by the restricted flow from pipe 7, the heat thus created vaporizing sufficient of the fuel so that the flame will soon move up to the space directly beneath the pilot ring 16, the flame projecting upwardly through the central opening in this pilot ring but remaining entirely within the fire-pot. This is the low or pilot flame which continues as long as the fuel supply is cut down to a minimum. When the supply of fuel and air is increased to an intermediate stage so as to provide a larger fuel pool in the pot bottom and a proportionately increased air supply, the flame will move up above the pilot ring 16, and the combustion will take place partly above and partly below the upper fire-ring 15. When the supply of fuel and air is increased to the maximum for the high-fire, the flame will burn in and directly below the central opening in the fire-ring 15 and extend above the pot into the combustion space thereover. This type of burner is now well known and forms no specific part of the present invention which is concerned primarily with improved means for controlling the flow of fuel and combustion air to the burner.

The air conduit B comprises a rectangular damper-casing 18 connected at its outlet end with the inlet end of the air tube 19 (see Fig. 2) the tube 19 extending through the furnace wall or door and being connected at its outlet end into the burner housing 11 (see Fig. 1). The inlet end of casing 18 is connected by bolts 20 or other suitable means with the housing of blower C so that the open inlet end 21 of casing 18 will register with the discharge opening 22 of the blower casing.

The bottom wall of casing 18 is cut away to provide a large air opening divided into two similar passages 23 and 24 by the substantially balanced shutter 25 mounted intermediately on shaft 26 pivoted transversely across the central portion of the opening. When shutter 25 is in the closed position shown in solid lines in Fig. 2, both halves 23 and 24 of the bottom opening will be closed. When the shutter is swung in a counterclockwise direction to the position indicated in dotted lines in Fig. 2, and in solid lines in Fig.

5, the openings or passages 23 and 24 will both be opened. The opening movement of shutter 25 is limited by the engagement of the upper wing 27 of the shutter with an adjustable screw 28 projecting down through the top wall of casing 18, or by any other suitable stop means. The upper wing 27 of the shutter is cut away or notched, as indicated at 29, so as to clear the oil pipe 7 which preferably is mounted longitudinally within the lower portion of the air conduit B. When the damper is moved to the horizontal or closed position, the cut-out portion 29 of the shutter is closed by a tongue 30 provided in the bottom wall of casing 18 (see Fig. 4). With the shutter 25 in its open position and before the fan or blower C is put in operation, air sufficient to support the burner at low or pilot flame is drawn by natural draft through the openings 23 and 24, and conduit B into the burner chamber. 10 The damper mechanism also includes a vane or baffle member 31 carried by a shaft 32 pivoted transversely across the upper portion of casing 18 between the blower and shutter 25. When the blower is not in operation, the vane 31 will hang vertically, as shown in dotted lines Fig. 2. When the blower is operating, the air under pressure from the fan will swing the vane 31 to the inclined position shown in solid lines, Fig. 2. The vane 31 when in this position, will cooperate with 15 the inclined shutter 25 to direct a large amount of the air under pressure from the fan through the bottom openings 23 and 24, thus cutting down the flow of air under pressure to the burner A. 20 Means, hereinafter described in detail, is provided for progressively swinging shutter 25 in a clockwise direction from the open position shown in dotted lines (Fig. 2) to the closed position shown in solid lines as the oil supply to the burner 25 is increased. As a result the lower wing 33 of shutter 25 will progressively close the opening 24 and at the same time the upper wing 27 of shutter 25 will close the other half 23 of the bottom opening so as to prevent the escape of pressure-air through these openings and at the same time 30 close the natural-draft inlet.

A mercury-tube switch 34 is suitably supported on one outer end of shaft 32 which carries the vane or baffle 31. This switch 34 will normally be enclosed in a housing 35 removably supported at one side of damper casing 18 (see Fig. 4). When the blower is not in operation and vane 31 is hanging vertically, the tube of switch 34 will be so inclined that the contacts 36 and 37 in one end portion of the tube will not be engaged by the mercury globule 38 (Fig. 5). However, when the blower is operating and vane 31 is swung to the inclined position the switch tube will be tilted so that the mercury globule 38 will join the contacts 36 and 37 and complete a control circuit (hereinafter described). The vane 31 may be notched or cut away, as indicated at 31' (Fig. 4) so as to clear the oil tube 7 when vane 31 swings to its vertical position. 40

The fan or blower C is preferably driven by the directly connected motor 39, the blower having an adjustable air intake at 40. However, when air intake 40 has once been satisfactorily adjusted, this adjustment will not normally be disturbed and the fan will be driven at substantially constant speed. All changes in the flow of air from the blower to the burner are accomplished by adjusting the swinging shutter 25 controlling the auxiliary air openings 23 and 24. 50

Within the housing 41 supported on base 1 ad-

10 adjacent the blower C is a chamber containing a pool of oil or other liquid fuel maintained at a substantially constant level by a float-valve mechanism, as is well known in this art. Oil from this pool flows by gravity through the control valve E and pipe 42 to the outer inlet end of pipe 7 and thence through this pipe to the burner pot 5. Valve E is shown in dotted lines in Fig. 1, and more in detail in Figs. 5 and 6. The valve E comprises a tubular portion 43 which projects downwardly below the level of the oil pool 44 so that oil will tend to flow through the opening 45 in tube 43. The valve stem 46 slideable in tube 43 is cut away at its lower end (Fig. 6) to provide a small upper slot 47 and a larger lower slot 47' extending through the lower end of the valve stem. When the valve stem is lowered to its extreme closed position, the small slot 47 will still register with opening 45 so as to permit a minimum flow of oil from pool 44 sufficient to maintain the pilot fire in the burner. As the valve stem 46 is progressively elevated from this lowermost position, more and more of the larger slot 47' will be brought into registry with opening 45 so as to progressively increase the oil flow to the burner.

15 The inner diameter of tube 43 is increased at 48 to provide a housing for the spring 49 confined between the shoulder at the lower end of recess 48 and a collar 50 adjacent the upper end of stem 46. Spring 49 constantly tends to open the valve, the valve being held closed against spring 49 by the operating lever 51 pivoted at 52 and positioned in the housing 41 (Fig. 1) supported above the valve housing 41. A pin 54 projecting laterally from valve stem 46 through a slot 55 in the upper portion of tube 43 is adapted to engage an adjustable stop-screw 56 to limit the opening movement of the valve. The closing movement of the valve is limited by the engagement of operating lever 51 with another stop-screw 57. It may here be noted that the valve operating and adjusting mechanism is, for the most part, shown diagrammatically in Fig. 5, and that actually the parts may be differently arranged and proportioned. A spring 58 normally swings the operating lever 51 in a clockwise direction so as to close the valve, and an adjusting screw 59 limits the opposite or counter-clockwise movement of lever 51. A pair of suitable electrically operated motors F and G are utilized for swinging the main operating lever 51 against the resistance of spring 58 to open the valve E. In the form here shown the motor F comprises a bi-metallic strip 60 anchored at one end 61 and adapted to warp or swing upwardly when heated by the passage of a suitable current through the heating coil 62. The free end of the bi-metallic strip 60 engages a projection 63 on lever 51 so as to swing lever 51 in a counter-clockwise or valve-opening direction until this movement is limited by the engagement of the bi-metallic strip 60 with an adjustable stop screw 64. This will permit the valve E to open until a small portion of the large slot 47' is in registry with opening 45 and a supply of oil sufficient to maintain an intermediate fire will be permitted to flow to the burner A. The motor G is here shown as similar to the motor F. When the bi-metallic strip 65 is heated by coil 66 it will engage the projection 67 of lever 51 and swing the lever further in a counter-clockwise or valve-opening direction. This will permit the valve to open to its maximum, this movement being limited by the engagement of pin 54 with the screw 56. A larger part of notch 47 in the valve stem 70

will now be in registry with openings 45 and the flow of oil through the valve to the burner will be increased so as to maintain the maximum or high-fire.

5 A lever 68 intermediately pivoted at 69 has its longer arm connected through link 70 with the outer end of crank arm 71 secured on the outer end of shaft 26 which carries the shutter 25. A substantially vertically extending operating rod 72 projects adjacent its ends through the end portions of valve-operating lever 51 and the shorter arm 73 of damper-operating lever 68. The outer end of lever 51 is confined between a fixed stop collar 74 on rod 72 and a compression spring 75 surrounding the upper portion of rod 72 and confined between lever 51 and an adjusting nut 76 threaded on the upper end of the rod. The end 73 of damper-operating lever 68 is connected with rod 72 through a similar yieldable connector including the spring 77.

10 As the operating lever 51 is swung upwardly or in a counter-clockwise direction to permit the valve E to open, the lever will operate through spring 75 to lift the rod 72 and thereby move the lever system 68, 70, 71 so as to swing the shutter 25 in a clockwise direction toward closed position. The operating arms of the lever system are so proportioned that the air flow to the burner will be increased or decreased in the desired proportion to the increase or decrease of the fuel flow caused by the adjustment of valve E. Preferably the parts are so proportioned that the shutter 25 will be completely closed before the valve E has reached its extreme open position, the final movement of lever 51 (after the shutter 25 is closed) slightly compressing the spring 75. As a consequence of this "over-travel" of the operating lever 51, on the return movement of lever 51, the valve-closing adjustment will commence before the shutter 25 starts to open. Therefore the decrease in the air supply to the burner will be retarded with respect to the decrease in the fuel supply so that there will be ample air to complete the combustion of excess fuel already delivered to the pot and the pool in the pot bottom will be reduced in size to the amount required for the lower flame before the air flow is cut down proportionately.

15 Referring again to the wiring diagram of Fig. 5, at 78 and 79 are shown the wires of a main power supply circuit. This power supply may be cut off by opening the main switch 80. The primary coil 81 of a transformer T is connected through leads 82 and 83 across the respective power mains 78 and 79. The secondary 84 of transformer T supplies low voltage current to the control devices hereinafter described.

20 The thermostat H is suitably positioned to respond to temperature changes in the room or space that is being heated by the burner A. The thermostatic member 85 will function, as the temperature falls, to successively move the arm 86 into engagement with the fixed contacts 87 and 88. One wire of the control circuits is permanently connected to the movable thermostatic member at 89. Assuming that the temperature has fallen to the point where thermostat contact 86 engages the fixed contact 87, a control circuit will be completed as follows: From the secondary 84 of transformer T through wire 90, thermostat contacts 86 and 87, wire 91, heater coil 92, and wires 93 and 94 back to the transformer-secondary 84. The heater 92 is part of a relay assembly K also comprising a bi-metallic strip 95 anchored at one end 96 and connected at its movable end through link 97 with the pivoted mercury switch

98. When heating coil 92 is energized, the bimetallic strip 95 will warp upwardly so as to lift link 81 and tilt the switch 98 so that the mercury globule will complete a circuit through the switch contacts 99 and 100. A fan-energizing circuit will now be completed as follows: From power main 78 through wire 101, fan-motor 38, wire 102, switch contacts 99 and 100 and wire 103 to the other power main 78. The fan or blower will now run continuously as long as the first mentioned control circuit is completed through thermostat H.

As soon as the blower C starts to operate, the hanging vane or baffle 31 will be swung to its inclined position so as to close the mercury switch 34, and this switch will remain closed as long and only as long as the blower C continues to operate. An energizing circuit for valve-operating motor F is now completed as follows: From the transformer through wire 90, thermostat contacts 86 and 87, wires 91 and 104, heating coil 62, wire 105, switch 34 and wire 94 back to the transformer. Motor F will now act to swing the lever 51 and permit valve E to open to its intermediate position. At the same time the mechanical lever connections will be actuated to partially close the shutter 25.

If there is a further drop in room temperature the thermostat H will cause arm 86 to contact with the second terminal 88 of the thermostat. An energizing circuit for valve-opening motor G will now be completed as follows: From the transformer through wire 90, thermostat contacts 86 and 88, wire 106, heating coil 66, wire 107 to wire 105 and thence, as before, through switch 34 back to the transformer. The motor G will now swing lever 51 to its limit in the counter-clockwise direction and permit the valve E to fully open. At the same time the previously described mechanical connections will completely close the shutter 25.

As the temperature within the heated space rises, the thermostat arm 86 will swing in the opposite direction and the contact 88 will first be disengaged so as to break the last-described energizing circuit for motor G. The spring 58 will now swing lever 51 clockwise to partially close valve E to its intermediate position. At the same time shutter 25 will be partially opened. If the rise in temperature is sufficient to cause thermostat H to break the connection between terminals 86 and 87, the energizing circuits for heat-motor F and relay K will both be broken. The valve E will now be moved to its closed position, that is only the minimum flow of oil sufficient to maintain the pilot-flame will be permitted. At the same time the blower C will cease to operate and shutter 25 will be moved to its most open position so that a free flow of air is admitted under natural draft through opening 23 to supply sufficient combustion air for the pilot-flame.

If at any time (regardless of temperature conditions and the positioning of thermostat H) the blower C should cease to operate either through breaking of the motor circuit or for any other reason, the vane 31 will swing back to its vertical position so as to open the switch 34. In that event both valve-opening circuits will be broken, or it will be impossible to complete these circuits at the thermostat H, and the valve E will be automatically closed so as to cut down the flow of oil to a minimum. At the same time shutter 25 will be opened and since the minimum flow

of oil can be adequately burned by the air flowing in through opening 23 under natural draft, there will be no accumulation of oil or fuel in the burner, except the small pool necessary to maintain the pilot-flame. Only this low fire can be maintained until the blower C is again able to function.

In the simplified system indicated in Fig. 7, the blower-motor 38 is not controlled by thermostat H but is connected permanently across the power mains 78 and 79 through wires 108 and 109. The blower will operate continuously as long as the main switch 80 is closed. The relay K and the control circuit first described are omitted entirely, otherwise the operating connections are the same as described in connection with Fig. 5. As in the first described system, the valve-opening circuits cannot be completed unless the blower is functioning to swing vane 31 and maintain switch 34 closed. The only difference in operation is that the blower runs continuously, even when the burner is on low fire, that is only the pilot is burning. At this time the excessive air from the blower will be dissipated through opening 24 in the bottom of damper-casing 18.

We claim:

1. In combination, a burner, means for delivering a fluid fuel to the burner, means for supplying combustion air to the burner including a blower and an air conduit leading from the blower to the burner, there being an auxiliary opening in a wall of the conduit between the blower and burner for admitting air under natural draft when the blower is not operating and permitting the escape of air under pressure from the blower, movable damper means for increasing or decreasing the effective size of said opening for controlling the flow of air to the burner, and electrically actuated motor means controlled by temperature changes in the space heated by the burner for moving the damper means to selected positions.

2. In combination, a burner, means for delivering a fluid fuel to the burner, means for supplying combustion air to the burner including a blower and an air conduit leading from the blower to the burner, there being an auxiliary opening in a wall of the conduit between the blower and burner, damper-means comprising a shutter intermediately pivoted across a central portion of said opening, said shutter when in open position directing air under pressure from the blower through the opening and admitting air under natural draft through the opening when the blower is not in operation, and when in closed position closing the opening, and electrically actuated motor means controlled by temperature changes in the space heated by the burner for moving the damper means to selected positions.

3. In combination, a burner, means for delivering a fluid fuel to the burner, means for supplying combustion air to the burner including a blower and an air conduit leading from the blower to the burner, there being an auxiliary opening in a wall of the conduit between the blower and burner, damper-means comprising a shutter intermediately pivoted to control the effective size of said opening, said shutter when in open position directing air under pressure from the blower through the opening and admitting air under natural draft through the opening when the blower is not in operation, and when in closed position closing the opening, said damper-means

also comprising a pivoted vane extending transversely of the conduit between the blower and shutter when the blower is not in operation, and being moved by air under pressure from the blower to a position where it cooperates with the open shutter to direct air from the blower through the opening, and means for moving the shutter to or from closed position.

4. In combination, a burner, valve-means for controlling the flow of fuel to the burner, damper-means for controlling the flow of air to the burner, thermostatically controlled means for adjusting the valve means, and mechanical connections between the valve-actuating means and the damper-means for adjusting the damper means as the valve is opened or closed to proportionately increase or decrease the flow of fuel and air to the burner, said mechanical connections comprising a spring means that is compressed by an additional valve-opening movement after the air-increasing damper adjustment is completed, said spring causing an initial valve-closing movement before the air-decreasing damper adjustment begins.

5. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner for admitting air under natural-draft and permitting the escape of air under pressure from the blower, normally-open damper means for controlling the effective size of said opening and directing the flow of air through the opening, and motor means including interconnecting means between the valve-means and damper means for substantially simultaneously adjusting said valve-means to increase the fuel flow and adjusting said damper means toward closed position to increase the air flow to the burner.

6. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner for admitting air under natural-draft and permitting the escape of air under pressure from the blower, normally-open damper means for controlling the effective size of said opening and directing the flow of air through the opening, and motor means responsive to temperature changes in the space heated by the burner and including interconnecting means between the valve-means and damper means for substantially simultaneously adjusting said valve means to increase the fuel flow and adjusting said damper means toward closed position to increase the air flow to the burner.

7. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner for admitting air under natural-draft and permitting the escape of air under pressure from the blower, normally-open damper means for controlling the effective size of said opening and directing the flow of air

5 through the opening, thermostatically controlled means for adjusting said valve-means, and mechanical connections between the valve-actuating means and the damper-means for closing the damper-means as the valve is opened, or vice versa, to proportionately increase or decrease the flow of fuel and air to the burner.

8. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner for admitting air under natural-draft and permitting the escape of air under pressure from the blower, normally-open damper means for controlling the effective size of said opening and directing the flow of air through the opening, thermostatically controlled means for adjusting said valve-means, mechanical connections between the valve-actuating means and the damper-means for closing the damper-means as the valve is opened, or vice versa, to proportionately increase or decrease the flow of fuel and air to the burner, said mechanical connections comprising a spring means for permitting an additional valve-opening movement after the damper is completely closed, and causing an initial valve-closing movement before the opening movement of the damper begins.

9. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner for admitting air under natural-draft and permitting the escape of air under pressure from the blower, normally-open damper means for controlling the effective size of said opening and directing the flow of air through the opening, thermostatically controlled means for adjusting said valve-means, mechanical connections between the valve-actuating means and the damper-means for closing the damper-means as the valve is opened, or vice versa, to proportionately increase or decrease the flow of fuel and air to the burner, and means for causing the valve-means to reduce the fuel flow to a minimum when the blower ceases to function.

10. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner, a shutter intermediately pivoted across a central portion of the opening, said shutter when in open position directing air under pressure from the blower through the opening before reaching the burner and admitting air under natural-draft through the opening when the blower is not operating, and when in closed position closing the opening, and means for substantially simultaneously adjusting said valve-means toward or from a fully open position and adjusting said shutter toward or from a fully closed position to proportionately increase or decrease the flow of fuel and air to the burner.

11. In combination, a burner, means for sup-

plying a fluid fuel to the burner, valve means for normally limiting the flow of fuel to the burner, means including an electric circuit and a pair of switches therein for controllably opening said valve-means to increase this fuel flow, means for supplying combustion air to the burner including a blower and a conduit for carrying the air stream from the blower to the burner, movable damper-means positioned in the conduit in the path of the air stream, thermostatic means for opening and closing one of the switches, and connections between the damper-means and the second switch for closing the second switch by movement of the damper means caused by the air stream and rendering the valve-opening means operable only while the blower is operating to product the air stream.

12. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the blower and burner, a movable shutter controlling the effective size of the opening, said shutter when in open position directing air under pressure from the blower through the opening and admitting air under natural-draft through the opening when the blower is not operating, and when in closed position closing the opening, a pivoted vane extending transversely of the conduit between the blower and shutter when the blower is not in operation, and being swung by air under pressure from the blower to a position where it cooperates with the open shutter to direct air from the blower through the opening, means comprising a thermostatically controlled circuit for adjusting said valve-means, mechanical connections between the valve-actuating means and the shutter for closing the shutter as the valve is opened, or vice versa, to proportionately increase or decrease the flow of fuel and air to the burner, and a switch in said valve-controlling circuit, said switch being operatively connected with the vane so that the switch will be closed when the blower is functioning and open when the blower is not functioning.

13. In combination, a burner, means for delivering a fluid fuel to the burner, valve-means controlling the flow of fuel to the burner, means for supplying combustion air to the burner including a blower and an air conduit leading from the blower to the burner, there being an auxiliary opening in a wall of the conduit between the

blower and burner, a movable shutter controlling the effective size of the opening, said shutter when in open position directing air under pressure from the blower through the opening and admitting air under natural-draft through the opening when the blower is not operating, and when in closed position closing the opening, a pivoted vane extending transversely of the conduit between the blower and shutter when the blower is not in operation, and being swung by air under pressure from the blower to a position where it cooperates with the open shutter to direct air from the blower through the opening, a thermostat responsive to changes in room temperature, means comprising an electric circuit closed by the thermostat at a predetermined temperature for starting the blower, means comprising a second circuit also closed by the thermostat for adjusting the valve-means to increase the flow of fuel to the burner, a switch in said second circuit operated by the vane so that the switch is only closed while the blower is functioning, and mechanical connections between the valve-actuating means and the shutter for closing the shutter as the valve is opened, or vice versa.

14. In combination, a burner, means for delivering a fluid fuel to the burner, means for supplying combustion air to the burner including a blower and an air conduit leading from the blower to the burner, there being an auxiliary opening in a wall of the conduit between the blower and burner, damper-means comprising a shutter intermediately pivoted to control the effective size of said opening, said shutter when in open position directing air under pressure from the blower through the opening and admitting air under natural draft through the opening when the blower is not in operation, and when in closed position closing the opening, said damper-means also comprising a pivoted vane extending transversely of the conduit between the blower and shutter when the blower is not in operation, and being moved by air under pressure from the blower to a position where it cooperates with the open shutter to direct air from the blower through the opening, and means responsive to temperature changes in the space heated by the burner for moving the shutter to or from closed position and simultaneously controlling the rate of fuel supply to the burner, said means including a switch operated by the pivoted vane.

DAVID J. HOWARD.
SAMSON J. JOHNSON.

CERTIFICATE OF CORRECTION.

Patent No. 2,251,055.

July 29, 1941.

DAVID J. HOWARD, ET AL.

It is hereby certified that error appears in the printed specification of the above numbered patent requiring correction as follows: Page 6, first column, line 17, claim 11, for the word "product" read --produce--; and that the said Letters Patent should be read with this correction therein that the same may conform to the record of the case in the Patent Office.

Signed and sealed this 23rd day of September, A. D. 1941.

(Seal)

Henry Van Arsdale,
Acting Commissioner of Patents.
